UNITED STATES PATENT OFFICE

2,362,514

CENTRIFUGAL COMPRESSOR

Donald F. Warner, Swampscott, Mass., assignor
to General Electric Company, a corporation of
New York

Application June 3, 1941, Serial No. 396,426

2 Claims. (Cl. 230—127)

The present invention relates to centrifugal compressors or blowers such as are used on aircraft for supplying air or like medium under pressure to a combustion engine or other consumer for air under pressure. More specifically the invention relates to the type of centrifugal compressors which have an impeller with a set of circumferentially spaced blades forming impeller passages and a diffuser with a set of vanes forming diffuser passages for receiving a medium impelled by the impeller and for converting part of the velocity energy of such medium into pressure energy. Such compressors, especially when used on aircraft, are operated at high speeds, for example of the order of 1200 feet per second peripheral speed and above. At such high speed the medium forced by the impeller into the diffuser passages due to the high relative speed between the impeller blades and the diffuser vanes may create considerable vibrations and shocks in these blades and vanes.

The object of my invention is to provide an improved construction and arrangement of centrifugal compressors of the type above specified whereby vibrations of the impeller blades and diffuser vanes are reduced to a minimum. This is accomplished in accordance with my invention by the provision of impeller blades having outer portions inclined toward the inner portions of the diffuser vanes. In a preferred embodiment the outlet edges of the impeller blades are inclined toward the inlet edges of the diffuser vanes, and in addition the outlet edges and the adjacent portions of the impeller blades are inclined toward radial planes in one direction, whereas the inlet edges and the adjacent portions of the diffuser vanes are inclined toward radial planes in the opposite direction. More generally the blades and vanes are inclined in opposite directions toward surfaces through their roots and perpendicular to the plane of rotation.

For a better understanding of what I believe to be novel and my invention, attention is directed to the following description and the claims appended thereto in connection with the accompanying drawing.

In the drawing, Fig. 1 illustrates a sectional view of a centrifugal compressor embodying my invention; Fig. 2 is a view along line 2—2 of Fig. 1; Fig. 3 is a view along lines 3—3 of Fig. 2; and Fig. 4 is a view along line 4—4 of Fig. 3.

The compressor comprises a casing having two halves 10 and 11 flanged together by means including a row of bolts 12. A central portion of

the casing forms a chamber with an inlet 13 for receiving air or like medium to be compressed. An impeller 14 is located in the impeller chamber and has a disc 15 with a plurality of circumferentially spaced blades 17 integrally formed thereon for impelling the medium conducted to the inlet 13 by forcing such medium radially outward by the action of centrifugal force. The medium discharged from the outer portion of the impeller is received by a diffuser 18 which converts part of the velocity energy of the impelled medium into pressure energy and discharges such medium to a discharge chamber or scroll 19 formed by an outer portion of the casing and having a discharge opening 20. The diffuser 18 has a wall in the form of a ring 21 supported on and secured to the casing half 10 by means including a plurality of bolts 22. A plurality of vanes 23 are secured to, in the present example integrally formed with, the ring 21 forming with an adjacent portion of the casing wall a plurality of diffuser passages 24.

Each diffuser vane 23 has an inlet edge 25 and each impeller blade 14 has an outlet edge 26. The edges 25 and 26 of the diffuser vanes and the impeller blades respectively in accordance with my invention are inclined toward each other. When viewed along line 3—3 of Fig. 2 as illustrated in Fig. 3, the inlet edges 25 of the diffuser vanes are inclined toward the left relative to the axial direction; whereas, the outlet edges 26 of the impeller blades 14 are inclined toward the right relative to the axial direction. During operation the impeller blades assume different positions relative to the diffuser vanes as the impeller is rotated an angle corresponding to the pitch of the diffuser vane. During such relative movement the flow pattern of the fluid in the adjacent portions of the impeller passages and the diffuser passages will change. This change in flow conditions is considerably reduced by bevelling the adjacent edges of the impeller and the diffuser in opposite directions.

As a further means to reduce vibration in accordance with my invention, I incline adjacent edge portions of the impeller blades and the diffuser vanes in opposite directions toward planes through the root of such edges and perpendicular to the plane of rotation. This is indicated in Fig. 2 and illustrated in detail in Fig. 4. The inlet edge of the diffuser vane 23 is inclined toward the left relative to a plane or surface 28 through its root and perpendicular to a plane of rotation 29, whereas the outlet

portion of the adjacent impeller blade 14 is inclined toward the right relative to a plane or surface 30 through the root of the blade and perpendicular to the plane 29. From another viewpoint both the impeller blades and the diffuser vanes, in particular the adjacent portion thereof; that is, the outlet portions of the impeller blades and the inlet portions of the diffuser vanes, are inclined toward a plane perpendicular to the axis of rotation, the outlet portions of the impeller vanes being inclined toward such plane in one direction and the inlet portions of the diffuser vanes being inclined toward such plane in the opposite direction. With such an arrangement of the adjacent edges and portions of the diffuser vanes and the impeller blades, a relatively small and smooth change of the flow pattern takes place as these vanes are moved relative to each other during operation. The fatigue of the vanes heretofore caused by the hammer-blow-like shocks of the compressed medium on the adjacent portions of the diffuser vanes and the impeller blades are materially reduced and the dependability and life of these parts are correspondingly increased. With the improved arrangement of the inlet and outlet edges of the diffuser and impeller respectively, the rise in temperature of the impeller medium on its passage through the compressor is sub-

stantially reduced, and the efficiency of the compressor accordingly is increased.

What I claim as new and desire to secure by Letters Patent of the United States, is:

- 5 1. Centrifugal compressor comprising a casing, an impeller located in the casing and having a plurality of circumferentially spaced blades, a diffuser located in the casing and surrounding the impeller for converting a part of the velocity
- 10 10 energy of a medium discharged from the impeller into pressure energy, the diffuser having a plurality of circumferentially spaced vanes, the diffuser vanes and the impeller blades having adjacent edges bevelled in opposite directions
- 15 15 toward the axis of rotation and the diffuser vanes and impeller blades having adjacent portions inclined in opposite directions with reference to planes through their roots and perpendicular to a plane of rotation.
- 20 2. Centrifugal compressor comprising a casing forming an impeller chamber and a diffuser chamber, an impeller with a plurality of circumferentially spaced blades located in the impeller chamber, and a diffuser with a plurality of circumferentially spaced vanes located in the diffuser chamber, the diffuser vanes having inlet portions with a bevelled edge and inclined toward a plane of rotation.
